UNITED STATES PATENT OFFICE.

CHARLES AHOLA, OF DETROIT, MICHIGAN.

SHIP CONSTRUCTION.

1,416,155.

Specification of Letters Patent. Patented May 16, 1922.

Application filed December 27, 1920. Serial No. 433,508.

To all whom it may concern:

Be it known that I, CHARLES AHOLA, citizen of Finland, residing at Detroit, in the county of Wayne and State of Michigan, 5 have invented certain new and useful Improvements in Ship Constructions, of which the following is a specification.

This invention relates to improvements in ship construction. The principal object is 10 to provide an indestructible ship, immune from disastrous attack by submarines or mines in time of war, and safe in event of collision. The invention provides a ship having a sectional keel yieldingly spaced 15 from the hull of the ship, the sections of the keel being relatively movable to take up shock, and the sections being secured to the hull so that they may be readily released therefrom. Shock absorbing mechanism is disposed about the hull, both above 20 and below the water line.

With the foregoing and such other objects in view as will be apparent from the description, my invention resides in the novel 25 construction combination and arrangement of parts hereinafter described and claimed, and illustrated in the accompanying drawings, in which;

Fig. 1, is a side elevation, parts being 30 broken away,

Fig. 2, is a top plan view,

Fig. 3, is a side elevation, with the keel 35 in section,

Fig. 4, is an end view of the ship,

Fig. 5, is an irregular vertical section 40 through the hull protecting mechanism.

Described in detail, numeral 1 denotes the hull of the ship and 2 the cabin. The hull 1 rests mainly on a base 3 carrying a marginal platform 4 having the fore and aft spool like deflectors 5 and 6, which are further supported by the upper platform 7, running entirely around the ship. At both 45 ends of the ship are disposed upper and lower sets of vertical tubular deflectors 8 and 9, at each side of the hull, said sets being separated by a spacer plate 10. Between these sets of deflectors 8 and 9. I provide two cover plates 11 and 12, spaced slightly from 50 one another and connected by a stout spring hinge 13, to platform 4, said hinge on each cover plate, serving to retain the free edges of the cover plates in frictional engagement with platform 7. Inside each cover 55 plate, are disposed a plurality of horizontal

rods 14, having their ends embedded in uprights 15 which extend from the cover plates to the hull, and upon each rod 14, a coil spring 16 is arranged with the ends thereof abutting or being secured to, the uprights 60 15. Deflectors 5, 6, 8 and 9 serve, in the event of collision, to cause the object struck to glance off to one side.

The keel comprises a plurality of sections, including a central section 17 and upwardly stepped side sections 18 rising therefrom. The sections extend longitudinally of the ship and are connected by a bridge plate 19 secured on the faces of the smaller sections 18. Each section is formed with a plurality of sockets 20, registering with perforations 21 in the bridge plate 19. The base 3 is formed with lateral depending portions 22 similar to, and at each side of, the keel sections, which portions are formed with 70 laterally opening sockets having hinged cover plates 20a. In each socket 20 is disposed an expansion spring 23 extending through the mouth of the socket and perforation in the bridge plate and abutting a 80 base plate 24 fastened to the under side of base 3, said sections being engaged by cables 25 which pass at one end of the ship through a conduit 26, to a binding post 27, and at the other end through a conduit 28, 29 and 85 are wound on a drum 30 in a housing 31, said drum being held in adjusted position by a latch 32.

The several keel sections are formed with registering apertures 33 provided with 90 covers 34, and in said apertures, and extending downwardly through the keel sections, are the leaves of the hinges 35 whereby the keel sections are adjustably secured to each other and to the bridge plate 19, said hinges 95 being formed with longitudinal slots 35a to slidably receive the hinge screws and permit relative movement of the sections. Plates 19 and 24 are spaced by the springs 23, permitting the keel as a whole to have a 100 vertical movement relative to the hull, making a shock absorber of the keel. The side walls of the larger sections 18 are formed with slots 36 in which blocks 37 are disposed. These blocks are carried by the keel sections 105 and are smaller than the slots to permit relative movement of the keel sections. Blocks 38, carried upon pins 39 embedded in the smaller keel sections, are disposed inside the depending lateral members 22 and are 110

adapted to engage with these members or the bridge plate 19 to limit the relative movement of the keel sections. The keel may be released from the hull, if damaged, by severing the cables 25. A further shock absorbing mechanism is formed by laterally extending brackets 40 at the upper side edges of the hull 1, between which, and the platform 7, coil compression springs 41 are disposed on guide bolts 42.

10 I claim:

1. In a ship, a hull, a keel, and means adjustably connecting said keel and hull whereby said keel is yieldingly spaced from the 15 hull.

2. In a ship, a hull, a sectional keel, the sections of said keel being relatively adjustable, and means for adjustably securing said keel as a unit, to the hull.

20 3. In a ship, a hull, a sectional keel adjustably and detachably secured thereto, the sections of said keel being relatively adjustable and stepped.

4. In a ship, a hull, a base for said hull, 25 lateral depending portions on said base, a keel disposed between said portions and

means for adjustably securing said keel to the hull.

5. In a ship, a hull, a base thereon having lateral depending portions at opposite sides, 30 a sectional keel disposed between said portions, said sections being relatively adjustable, and means for adjustably securing said keel to the base.

6. In a ship, a hull, a base therefor having lateral depending portions provided with sockets, a sectional keel disposed between said portions, the sections of said keel being formed with sockets and being relatively adjustable, a perforated bridge 40 plate connecting said keel sections, springs disposed in said sockets and through the perforations of said bridge plate and abutting said base, and cables connecting said springs and the hull.

45 In testimony that I claim the foregoing as my own I have hereto affixed my signature in the presence of two subscribing witnesses.

CHARLES AHOLA.
